(57) **CLAIM**

The ornamental design for the can guard, as shown and described.

DESCRIPTION

FIG. 1 is a perspective view of the can guard, as used on a can and in accordance with the invention;

FIG. 2 is an elevational top view thereof;

FIG. 3 is an elevational front view thereof;

FIG. 4 is an elevational rear view thereof;

FIG. 5 is an elevational side view thereof, the other side being a mirror image thereof;

FIG. 6 is an elevational bottom view thereof, and,

FIG. 7 is a rotated elevational bottom view thereof.

The broken lines in the Figures are for illustrative purposes only and form no part of the claimed design.
